UNITED STATES PATENT OFFICE.

JOHN F. APPLEBY, OF LORENA, OKLAHOMA.

COTTON-PICKING FINGER.

No. 908,638.

Specification of Letters Patent. Patented Jan. 5, 1909.

Application filed January 27, 1908. Serial No. 412,708.

To all whom it may concern:

Be it known that I, JOHN F. APPLEBY, citizen of the United States, residing at Lorena, in the county of Beaver, Oklahoma, have invented a certain new and useful Improvement in Cotton-Picking Fingers, of which the following is a full, clear, concise, and exact description, reference being had to the accompanying drawings, forming a part of this specification.

My invention relates to cotton picking fingers, and has for its object the provision of an improved finger that will be more suited to the picking of cotton than the fingers hitherto devised.

I will explain my invention fully by reference to the accompanying drawing, in which the preferred form of cotton picking finger is shown as constructed in accordance with my invention, the process of producing the finger and the construction of the finger being explained in connection with the drawing.

In the drawing—Figure 1 is a view in elevation of a finger constructed in accordance with my invention, the base portion of the finger being broken away for lack of room. Fig. 2 is a view in the direction of arrow 2 of Fig. 4, illustrating one step in the process of constructing the finger. Fig. 3 is a view on line 3 3 of Fig. 2 illustrating the same process step shown by Fig. 2. Fig. 4 is a plan view illustrating the process step illustrated in Figs. 2 and 3. Fig. 5 shows the structure of Fig. 4 after a groove has been formed to complete the toothed construction. Fig. 6 is a cross-sectional view on line 6 6 of Fig. 5.

Like parts are indicated by similar characters of reference throughout the different figures.

In the formation of the finger, a tapered bar, circular in cross-section, is selected, the larger end *a* of the bar constituting the base of the finger, the base portion being desirably of uniform diameter throughout, the balance of the finger tapering from the base portion toward the point *c*. The teeth are formed by means of a serrating tool *d*, whose striking end has two striking surfaces *e* *e'* that are desirably disposed at an angle approximating 80 degrees. The ridge *f* that intervenes between the striking surfaces *e* *e'* constitutes the cutting edge of the serrating tool or chisel. This cutting edge is impressed upon the rod that is to form the finger at an angle

of about 45 degrees with respect to the axis of the rod, so that teeth are formed upon the rod that are obliquely disposed with respect to the length of the finger. The cutting edge *f* of the tool is so rested upon the finger and the tool is so driven, that each cut upon the bar made by the tool constitutes a chord of the circle defining the shape of the finger in cross-section. The force that drives the tool into the metal of the rod is directed in a line that is substantially included within a plane containing the axis of the finger and the radius of the circle which bi-sects the chord above mentioned, in which way the tool is caused to strike a square blow upon the rod. Not only is the striking force given the direction indicated, but the tool is inclined at an angle of about 10 degrees from the vertical, so that the advanced striking surface *e* will raise the metal as indicated at *g* in Fig. 2, while the rear striking surface *e'* will partially lay the metal just previously raised by the striking surface *e*. The tool is caused to descend into the rod a distance desirably sufficient to raise the metal by the action of the striking surface *e* enough so that when the raised metal is partially depressed by the striking surface *e'*, the teeth will project a slight distance beyond the perimeter of the rod as indicated most clearly in Fig. 6. The tool is moved along the rod longitudinally thereof and desirably in a straight line after it makes each indentation. As the ridges thus formed along the length of the bar present no barbs, I cut away a part of each ridge so as to form thereon a picking barb or point such as indicated at *h* in Fig. 6. These ridges are desirably cut away by forming a groove *i* longitudinally of the rod, which groove not only removes enough of the ridges formed by the striking tool, to create the picking points *h*, but is also desirably extended into the metal of the rod a sufficient extent so as well to expose the points *h* to the cotton. The groove *i* is preferably of V-shape, as indicated most clearly in Fig. 6, so that no material that is gathered by the picking barbs may find permanent lodgment in the groove and so that no material that otherwise finds access to the groove may find permanent lodgment in the groove, the diverging walls of the groove preventing material from securing an anchorage within the groove.

It will be seen that I have provided a process for producing cotton picking fingers, which consists in impinging a serrating tool

obliquely upon a metal rod, causing the serrating tool to strike up metal from the rod each time the tool is impinged upon the rod, causing the serrating tool while making the 5 next cut partially to restore the metal it has previously raised and forming a V-shaped groove through the teeth and a solid portion of the finger. As a result of this process, I am enabled to produce a cotton picking finger in the form of a tapered rod circular in 10 cross-section, provided with teeth formed therein in a row extending longitudinally thereof, and a V-shaped groove cut into the rod having one wall facing the teeth, the opposite wall of the groove being formed by the teeth, the points of the 15 teeth projecting beyond the perimeter of the rod.

Having thus described my invention, I claim as new and desire to secure by Letters 20 Patent:

1. A cotton picking finger in the form of a rod provided with teeth formed therein in a row extending longitudinally thereof, and a V-shaped groove cut into the rod having 25 one wall facing the teeth, the opposite wall of the groove being formed by the teeth, the points of the teeth projecting beyond the perimeter of the rod.

2. A cotton picking finger in the form of a 30 tapered rod circular in cross-section provided

with teeth formed therein in a row extending longitudinally thereof, and a V-shaped groove cut into the rod having one wall facing the teeth, the opposite wall of the groove being formed by the teeth, the points of the 35 teeth projecting beyond the perimeter of the rod.

3. A cotton picking finger in the form of a rod provided with teeth formed therein in a row extending longitudinally thereof, and a 40 V-shaped groove cut into the rod having one wall facing the teeth, the teeth entering into the formation of the opposite wall, the teeth projecting beyond the perimeter of the rod.

4. A cotton picking finger in the form of a 45 tapered rod circular in cross-section provided with teeth formed therein in a row extending longitudinally thereof, and a groove cut into the rod having one wall facing the teeth, the teeth entering into the formation of the opposite wall, the teeth projecting beyond the 50 perimeter of the rod.

In witness whereof, I hereunto subscribe my name this 3rd day of January A. D., 1908.

JOHN F. APPLEBY.
